(57) **CLAIM**

The ornamental design for a measuring cup as shown and described.

DESCRIPTION

FIG. 1 is a perspective view of a first embodiment of a measuring cup in accordance with my design;

FIG. 2 is a front elevational view thereof;

FIG. 3 is a rear elevational view thereof;

FIG. 4 is a left elevational view thereof;

FIG. 5 is a right elevational view thereof;

FIG. 6 is a bottom plan view thereof; and

FIG. 7 is a top plan view thereof;

FIG. 8 is a perspective view of a second embodiment of a measuring cup in accordance with my design;

FIG. 9 is a front elevational view thereof;

FIG. 10 is a rear elevational view thereof;

FIG. 11 is a left elevational view thereof;

FIG. 12 is a right elevational view thereof;

FIG. 13 is a bottom plan view thereof; and,

FIG. 14 is a top plan view thereof.

1 Claim, 14 Drawing Sheets
